CLAIM

I claim the ornamental design for a mobile phone holder, as shown and described.

DESCRIPTION

FIG. 1 is a perspective view of a mobile phone holder, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention;

FIG. 6 is a top plan view of the invention; and,

FIG. 7 is a bottom plan view of the invention.

The broken line showing of a portion of a cell phone in FIG. 1 is for illustrative purposes only and forms no part of the claimed design. The broken lines on the hood and clip features throughout the drawing figures represent stitching and are part of the claimed design.
